UNITED STATES PATENT OFFICE.

MAX HIMOFF, OF NEW YORK, N. Y.

DRILL-PRESS.

1,032,410.

Specification of Letters Patent. Patented July 16, 1912.

Application filed July 8, 1911. Serial No. 637,498.

To all whom it may concern:

Be it known that I, MAX HIMOFF, a citizen of the United States, and resident of New York city, borough of Manhattan, in the county of New York and State of New York, have invented certain new and useful Improvements in Drill-Presses, of which the following is a specification.

The object of my invention is to provide a drill press wherein the drills may be adjusted to drill holes in circles or in parallel rows, or in other relative positions, at required distances apart, and wherein also a portion of the drills may be so adjusted or located that a relatively large number of holes may be drilled in substantial alinement.

My invention comprises novel details of improvement and combinations of parts that will be more fully hereinafter set forth and then pointed out in the claims.

Reference is to be had to the accompanying drawings forming part hereof, wherein,

Figure 1 is a plan view of a multiple drill press embodying my invention, showing the series of drilling devices arranged to drill holes in parallel rows or in circles; Fig. 2 is a side view, partly broken, looking to the left of the line *a*, *a*, in Fig. 1, and Fig. 3 is a front view showing the drill-sections extended into alinement.

Similar numerals of reference indicate corresponding parts in the several views.

At 1 is a suitable base or column shown provided with a table or work support 2 which may be raised and lowered and held in set position by any suitable or well known means. Upon table 2 any desired number of columns 3 are provided, shown rising from base member 1^c and located in parallel alinement and braced at their upper ends by the transverse member 4. The drill chucks 5 are carried by the columns 3 so as to have adjustment radially and laterally with respect to the axes of the drills. For this purpose the chucks 5 are carried by spindles 6 supported by laterally extending arms 7 adjustably supported upon the columns 3. The arms 7 are shown mounted to slide upon guides 8 carried at the sides of sleeves 9 that are rotatively mounted upon columns 3 and may be held in set position upon said columns by means of nuts or the like 10, whereby the drills may be adjusted radially of their axes or tangentially with respect to the axes of

columns 3, and may be adjusted laterally or in circles with respect to the axes of columns 3.

Any suitable or well known means may be provided for raising and lowering the drill chucks by means of the handles 11. 60 The drill spindles are rotated by any suitable means, and in the arrangement shown telescopic shafts 12 connect at 13 with the means for rotating the drills and at 14 said shafts connect with spindles 15 journaled in 65 bearings 16 and provided with gears 17 meshing with gears 18, the bearings 16 being shown carried by brackets 19 supported upon the member 4; or any other well known gearing or belt and pulley connections may 70 be used for the purpose. These drill operating devices and the arms that support the same may be made in accordance with the drill press disclosed in my application Serial No. 509,911, filed July 22, 1909, if desired. 75 The gears 18 are carried by a shaft 20 mounted in suitable bearings upon brackets 21, supported by member 4, said shaft being shown provided with pulleys 22 to receive a belt from pulleys 23 secured on 80 shaft 24 journaled in bearings supported by columns 1, said shaft being shown as also provided with fast and loose pulleys 25.

3^a indicates a series of columns corresponding to the columns 3 and supported by 85 a member 1^b movably carried upon base 1 and adapted to extend over a base 1^a that is located at a suitable distance from and in line with base 1 and provided with a table or work support 2^a with means for operating and supporting the same corresponding to that provided for base 1. The member 4^a at the upper end of columns 3^a corresponds to member 4. The columns 3^a are provided with drill chucks 5^a, spindles 6^a, arms 7^a, 95 guides 8^a, sleeves 9^a, nuts 10^a, and the operating connections 11^a, 12^a, 13^a, and the gearing 17^a, 18^a, corresponding to the similar parts and gearing before described.

The members 1^b and 4^a are connected with 100 the members 1^c and 4 by a hinge member 26 that is shown journaled at opposite ends upon rods or pintles 27, 27^a connected respectively with members 1^c, 4, and 1^b, 4^a; see Fig. 3. The member 4^a has brackets 21^a supporting 105 shaft 20^a that carries the gears 18^a in mesh with the gears 17^a of drill shafts 12^a. The swinging member 1^b is also provided with bearings supporting the shaft 24^a having pulleys 23^a, and shaft 20^a has pulleys 22^a. 110

Shaft 24 has a fast pulley 28 to receive a belt for driving fast pulley 28^a on shaft 24^a. Means are provided for holding the swinging drill devices 5^a, etc., parallel with the drilling devices 5, etc., for which purpose I have shown a bar 29 to firmly connect the member 1^b with the member 1^c at the end opposite hinge 26 when the parts are in the position shown in Figs. 1 and 2. This bar 29 may be provided with hooks 29^a (Fig. 2) to engage studs or keepers 29^b upon the members 1^b, 1^c. The hinge 26 and keeper 29 are of such dimensions that the series of columns 3^a will be spaced from the series of 15 columns 3 as desired, and may be made interchangeable in size for different classes of work. In the arrangement shown a belt is to connect pulleys 22, 23, and when the swinging drill members are parallel with 20 the drill members 3, etc., a belt connects the pulleys 22^a, 23^a, and at that time a belt is adjusted upon the alined pulleys 28, 28^a, whereby all the drills may be simultaneously operated. Provision is also made for 25 operatively connecting shafts 20, 20^a, when the different series of drill members are alined, as in dotted lines in Fig. 1 and in full lines in Fig. 3. This connection is represented at 30, and may be in the form of 30 a bar having a squared end adapted to enter a similar socket 20^b at the end of shaft 20 and provided with a socket 30^a to receive the squared or keyed end 20^c of shaft 20^a. The base 1^a is shown provided with a rest 35 1^d to receive the member 1^b when the parts are in the position shown in Fig. 3, to which rest the member 1^b may be secured by a bolt or in any other suitable manner. When the parts are arranged as shown in Figs. 1 and 40 2, with the series of columns 3 and 3^a spaced in parallelism, their corresponding chucks may be adjusted in various positions with respect to each other, either in parallel lines for drilling parallel rows of holes, or in circular, oval or other relation for drilling correspondingly arranged holes, as for drilling holes in flanges and the like. As the arms 45 7, 7^a may be adjusted in a direction tangentially or transversely with respect to the axes of the columns 3, 3^a, and may also be 50 swung to the right or left, it will be understood that a range of adjustment for the various drills may readily be made, and all the drills may rotate together by the arrangement of the various pulleys set forth. When the two series of drilling devices are 55 to be placed in alinement the belt connecting pulleys 28 and 28^a is removed, keeper 29 is released, and the members 1^b and 4^a 60 are swung on the hinge 26 over the rest 1^d, and then the bar 30 is operatively connected with the shafts 20, 20^a, as shown in Fig. 3, whereby both said shafts will be operated by the belt passing over pulleys 22, 23 so 65 that the drills will all operate in unison,

and said drills may be adjusted with respect to columns 3, 3^a, either in a straight line or in such other relation as may be required for the work upon tables 2, 2^a. It will thus be understood that by a simple adjustment 70 of the series of drills 5, 5^a I am enabled to provide a multiple-drill press having various capacities for drilling either simultaneously upon the same work, or simultaneously upon different pieces of work upon 75 the two tables, and also that when work is to be performed upon one of the tables only the drilling devices 5^a may be swung away from the drilling devices 5.

While I have illustrated a practical embodiment of my invention it will be understood that changes may be made in the arrangements set forth, within the scope of the appended claims, without departing from the spirit of my invention. 80

Having now described my invention what I claim is:—

1. A multiple-drill press comprising a series of drilling devices, means for operating each of said drilling devices, a second 90 series of drilling devices, a movable member supporting the latter separate from the first named drilling devices to have simultaneous movement in a lateral direction toward and from the first named series of 95 drilling devices, and means for operating the second named series of drilling devices.

2. A multiple-drill press comprising a base, a series of drilling devices carried thereby, means for operating said drilling 100 devices, a second series of drilling devices, a movable member movably supporting the second series of drilling devices in relation to the first named drilling devices, means for retaining the second named series of drilling devices in parallel relation to the first named drilling devices, and means for supporting the second named drilling devices in substantial alinement with and all at one end of the first named drilling devices. 105

3. A multiple-drill press comprising a base, a series of drilling devices carried thereby, a second series of drilling devices, a hinge supporting the second named series of drilling devices upon said base, means for retaining the second named drilling devices in parallel relation to the first named drilling devices, and means for retaining the second named drilling devices in extended 115 relation to the first named drilling devices. 120

4. A multiple-drill press comprising a base, a plurality of columns carried thereby, drilling devices adjustable separately with respect to said columns, means for operating the drilling devices, a second series of columns, means for supporting said columns to have movement relatively to the first named series of columns, drilling devices adjustably carried by the second named columns, 125 means for operating said drilling devices, 130

means for retaining the second named series of columns and drilling devices in juxtaposition to the first named columns, and means for retaining the second named columns and 5 drilling devices in substantial alinement with the first named columns.

5. A multiple-drill press comprising a base, a series of columns carried by the base, drilling devices adjustably carried by said 10 columns, a shaft, drill operating mechanism operated by said shaft, a second series of columns, drilling devices adjustably carried by said columns, a shaft adjacent said columns, operating devices operated by said 15 shaft for rotating said drilling devices, means movably connecting the second named columns with the first named columns, means for retaining said series of columns in parallel relation, means for retaining the movable 20 columns in alinement, and means for connecting said shafts to operate them in unison.

6. A multiple drill press comprising a

base, a series of columns carried by the base, drilling devices adjustably carried by said 25 columns, driving mechanism for said drilling devices, members movably connected with said base, a series of columns connected with said members, drilling devices adjustably connected with said columns, driving 30 mechanism connected with said members, means for retaining said members and columns in parallel relation to the first named columns, a base at a distance from the first named base and alined therewith, and provided with a rest for one of the movable 35 members, and means for connecting the operating means of said series of drills.

Signed at New York city, in the county of New York, and State of New York, this 40 6th day of June, A. D. 1911.

MAX HIMOFF.
